UNITED STATES PATENT OFFICE.

WILLIAM HENRY JOHNSON, OF HILO, TERRITORY OF HAWAII.

LINOTYPE-MACHINE.

1,196,547.

Specification of Letters Patent. Patented Aug. 29, 1916.

Application filed May 9, 1916. Serial No. 96,330.

To all whom it may concern:

Be it known that I, WILLIAM H. JOHNSON, a citizen of the United States, and a resident of Hilo, in the island of Hawaii, Territory of Hawaii, have invented certain new and useful Improvements in Linotype-Machines, of which the following is a specification.

My invention relates to the melting pot of a linotype machine whence the molten metal is pumped to the mold for forming the slugs through the medium of arbitrarily arranged matrices, and the main object thereof is to provide simple though efficient means for preventing dirt, scum, or dross, on the surface of the molten metal from passing to the pump and to the mold, thereby insuring clean slugs and a consequent increase of output of the machine.

My invention is fully described in the following specification, of which the accompanying drawings form a part, in which like characters refer to like parts in each of the views, and in which:—

Figure 1 is a vertical section taken through the melting pot of a linotype machine provided with my invention; and Fig. 2 is a detached, perspective, view of my attachment.

In the drawings forming a part of this application I have shown a melting pot 3 within which is arranged a pump well 4 for a pump plunger 5 operable by means of the rod 6, said well being perforated at 7 to communicate with the pot 3, and being in communication with the mouth 8 adjacent the mold, not shown, by means of a passage 9, these parts all being of conventional form.

My attachment comprises a corrugated cylinder 10 open at its ends and of an interior diameter equal to the external diameter of the well 4 and over which it is forced and upon which it is frictionally held, said cylinder extending upwardly a material distance above the normal level X of the molten liquid, as shown at X² and to a considerable depth below said level as shown at X³, whereby no dirt, scum, or dross upon the surface of the molten metal can enter the cylinder 10.

50 Inasmuch as the inward convolutions of

the cylinder walls bear against the exterior 55 of the well 4 passages are provided through the outward convolutions between the cylinder and the well for the molten metal to pass upwardly from the lower edge of the cylinder 10 to the interior thereof in the 60 natural tendency of the molten metal to maintain its level interiorly and exteriorly of the cylinder, and I may provide perforations 11 adjacent the lower edge of the cylinder to aid in this result. 65

In view of the extension of the cylinder above and below the level X only clean molten metal can pass to the interior of the cylinder and thence, by means of the pump, to the mold, and the slugs are therefore all 70 free from dirt or dross.

My invention is readily attached to the machine, requires no change in the latter, is very efficient in result, and comparatively inexpensive, and, while I have shown a preferred construction thereof, I do not limit myself thereto but may make changes thereof as long as I do not depart from the spirit of the invention, nor from the scope of the appended claims. 75 80

Having fully described my invention, what I claim as new, and desire to secure by Letters Patent, is:—

1. The combination with a melting pot of a linotype machine having a pump well 85 therein, of a cylinder held on said pump well and extending above and below the level of the molten metal for preventing the passage of dirt or dross to the pump.

2. The combination with a melting pot of 90 a linotype machine having a pump well therein, of a corrugated cylinder in frictional engagement with said well to prevent the passage of dirt or dross to the pump.

3. The combination with a melting pot of 95 a linotype machine having a pump well therein, of a cylinder on said pump well providing passages between the same and said well for the molten metal and extended above and below the level of the metal. 100

In testimony whereof I have signed my name to this specification.

WILLIAM HENRY JOHNSON.
